US00D605591S

(12) **United States Design Patent**
Mai et al.

(10) **Patent No.:** US D605,591 S
(45) **Date of Patent:** ** Dec. 8, 2009

(54) **BATTERY CONNECTOR**

(75) Inventors: **Yuan Li Mai**, Tu-Cheng (TW); **Hsin Tsung Ho**, Tu-Cheng (TW)

(73) Assignee: **Cheng Uei Precision Industry Co., Ltd.**, Taipei Hsien (TW)

(**) Term: **14 Years**

(21) Appl. No.: **29/311,588**

(22) Filed: **Apr. 24, 2009**

(51) LOC (9) Cl. **13-03**

(52) U.S. Cl. **D13/120**

(58) **Field of Classification Search** D13/118-121, D13/133, 146-147, 184, 199; 439/83, 108, 439/166, 500, 577, 630, 660, 680, 700, 773.1, 439/862

See application file for complete search history.

(57) **CLAIM**

The ornamental design for a battery connector, as shown and described.

DESCRIPTION

FIG. 1 is a perspective view of a battery connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view of the battery connector showing our new design; and,

FIG. 9 is a perspective view showing the battery connector being mounted on a printed circuit board.

The broken lines in the Figures are for illustrative purposes and form no part of the claimed designs.
